UNITED STATES PATENT OFFICE.

DAVID ARANGO, OF HABANA, CUBA.

STOVE.

Application filed December 15, 1920. Serial No. 430,935.

To all whom it may concern:

Be it known that I, DAVID ARANGO, a subject of the King of Spain, and resident of Habana, Cuba (whose post-office address is 5 #121 Neptuno Street, Habana, Cuba), have invented certain new and useful Improvements in Stoves, of which the following is a specification.

This invention relates to improvements in 10 stoves for drying materials and more particularly to a stove for drying the sugar-cane bagasse and its main object is to provide an apparatus for drying the sugar-cane bagasse as it comes from the sugar-cane mills, 15 before using the same as a fuel for the furnaces of the steam boilers in the sugar-cane mills.

An object of the invention is to provide an 20 apparatus so constructed as to be capable of wholly drying within the same the moist bagasse within a relatively short time.

Another object of the invention is to provide the apparatus with means for automatically taking out therefrom the dried 25 bagasse ready for being used as a fuel.

A further object is to provide means to permit a continuous and complete agitation of the mass of bagasse during the drying operation.

30 A still further object of the invention is to provide an improved construction of the apparatus whereby the hot gases of the combustion will not be led directly to the chimney but caused to follow a longer course 35 and thereby exert a slower and more efficient action on the moist bagasse.

The invention is described with reference to the figures of the annexed drawings, in which:

40 Fig. 1 is an upper plan view of the stove.
Fig. 2 is a vertical cross section on line 2—2 of Fig. 1.

Fig. 3 is an end elevation of the apparatus forming the subject matter of this invention.

45 Fig. 4 is a vertical cross section on line 4—4 of Figs. 1 and 6.

Fig. 5 is a vertical cross section on line 5—5 of Fig. 1.

50 Fig. 6 is a side elevation of said apparatus.
Fig. 7 is a longitudinal vertical section on line 7—7 of Fig. 1.

The stove forming the subject matter of this invention is of elongated shape and rectangular section, and its walls and floor 55 are made of refractory brick. In the front wall 1 of the stove is provided an upper

outlet 2 having a counterweighted door 3 which opens from the inside to the outside and on the rear wall 1' is provided a lower registering opening 4 the lower side of 60 which is level with floor 1" of the stove. The roof 2' of the stove forms a plane arch provided with separated registering openings 5 and an opening 6 for the inlet of the moistened bagasse to be dried, this opening 65 being provided with a hopper 7 provided with a counterweighted valve 7' which opens from outside to inside. In the side walls of the stove are provided the openings and registering doors 8 and 9 to facilitate inspection and cleansing thereof. On the roof 2' of the stove is a cover 10 which communicates through a horizontal tubular conduit 10' with a chimney 10" located at the exterior of the stove and designed for expelling the combustion gases and the water vapor of the moistened bagasse when the same dries out. On the sides of the stove there are exteriorly arranged supporting frames 11 and 12 on whose ends are provided 70 bearings on which are mounted horizontal shafts 13 and 14 through the body of the stove, there being arranged on each end of each one of these shafts, inside of the stove, sprocket wheels 15 and 16 on which runs a metal endless belt 17 in a longitudinal direction with respect to the stove and inside thereof and opposite the outlet 2. The upper run of said endless belt bears on a plurality of supporting and guiding rollers 18 mounted on shafts 19 transversely and horizontally to the stove and very close to one another which rotate on bearings 20 arranged on the intermediate beams 21 of each frame 11 and 12, and at its lower part the belt runs 75 on supporting and guiding rollers 22 which are mounted on horizontal shafts 23 rotatory on bearings 24 arranged on the lower beams 25 of each one of the said frames 11 and 12, whereby, as clearly illustrated in Fig. 7 of 100 the drawings, the belt 17 is tense at its upper half and bears and runs loosely at its lower half upon the rollers 22.

Slow motion is imparted to the belt 17 by means of a sprocket wheel 26 secured to the shaft 13, which in turn receives the motion through a chain gearing from another wheel 27 of a convenient power source designated in the drawings by the letter W.

A horizontal partition 30 divides the stove 110 into two compartments, an upper one 28 and a lower one 29, this partition being located

2

between the two series of shafts 14 and 15 and leaving at its ends free spaces 31 and 32 for communication between the upper and lower compartments, the main object of said partition being that the gases of the combustion be not led direct to the chimney 10" but that they should run throughout the stove, first through the lower compartment 29 from the front to the rear and then the 10 upper compartment 28 from the rear to the front so as to cause thereby an effective drying action. The partition 30 can be constructed of any suitable material, such as metal plates.

15 On the upper beam 21 of the outer frame 11 are secured brackets 34 having bearings on which rotate a long horizontal shaft 35 longitudinal with respect to the stove. On said shaft, and separated from each other, 20 are arranged the bevel gear wheels 36 meshing at right angle with bevel gear wheels 37 fixed on the corresponding ends of a plurality of horizontal shafts 38 transversely to the stove independent from each other and 25 separated apart, which are mounted on bearings 39 disposed on the upper beams 33 of each supporting frame 10 and 11. On the said shafts 38 are arranged agitating blades 40 which operate in the manner that 30 will be hereinafter explained. The long shaft 35 receives a rotary motion from a wheel 136 secured on one of its ends which receives motion through the wheel 137 and endless belt or chain 138 from the engine 35 system W. The lower compartment 29 of the stove communicates through a passage 41, whose inner walls are made of refractory brick, with the fire box 42 of a furnace located in an excavation 44 to which access 40 is had through a ladder 45, said furnace being provided at its upper part with a hopper 46 for feeding it with fuel in the event the same is of dry bagasse. 47 and 48, designate respectively the fire-box door, and the 45 door of the ash-pit. The furnace is designated 50.

The operation of this stove is as follows: After feeding the moistened bagasse from the hopper 7 through the counterweighted lock 7' this material falls on the upper part 50 of the metal belt 17 which is constantly advancing upon the wheels 15 and 16 and in the meantime the agitating blades 40 fixed 55 on the shafts 38 will keep a constant agitation of the layer of moistened bagasse traveling with the belt. The combustion gases from the furnace 43 will have access from the same through the passage 41 to the lower compartment 29 of the stove and will travel 60 throughout said compartment in the direction indicated by the arrows in Fig. 7, passing to the compartment 28 through the open space 31, and exert its action therein on the bagasse upon the belt 17, and then travels 65 to the chimney 10" from the conduit 10',

carrying also therewith the water vapor expelled by the bagasse when drying. In the meantime, the bagasse travelling on the belt 17 upon reaching the front opening 2, that is, in the point where the belt turns down, 70 will be discharged from the belt on its downward movement against the counterweighted door 3 and will push the same, falling outwards and being gathered in a convenient manner for its subsequent treatment. 75 The registering doors indicated with numerals 4, 5, 8 and 9 provide means for a proper cleansing and inspection of the stove.

Having thus described my invention and the manner in which the same is carried out, 80 what I desire to protect by Letters Patent is all that which may fall within the scope of the appended claims.

What I claim is:

1. A stove for drying materials on an 85 endless longitudinally traveling belt arranged in the stove, the latter having an opening for feeding upon the belt the material to be dried; means for creating a continued agitation of the layer of material 90 upon the belt; heating means in communication with the stove; means for causing the hot gases of the combustion to move in the interior of the stove therein first from the front to the rear and then from the rear to 95 the front; and means for discharging the gases of the combustion and the water vapor expelled from the material.

2. A stove for drying materials constructed of refractory material provided at its interior with a traveling metal endless belt 100 longitudinally arranged; means for imparting a slow motion to said belt; closely spaced rolls for maintaining tense the upper half of the belt, and rolls widely spaced 105 apart for maintaining loose the lower half of the belt; said stove having an opening on the upper rim part for feeding the material to be dried upon the belt and also having registering openings; an outlet in the front 110 part opposite the belt and provided with a counterweighted door, a horizontal partition dividing the stove in two compartments upper and lower leaving end openings 115 connecting both compartments; heating means in communication with the lower compartment of the stove; means for discharging out of the stove the combustion gases and water vapor expelled from the materials to be dried; and a plurality of agitating elements 120 arranged above the belt for maintaining a continued agitation to the layer of material upon the belt, and means for imparting rotatory motion to said agitating members.

3. A stove for drying materials constructed on its exterior of refractory material; a metal endless belt mounted inside of the stove on sprocket wheels arranged on horizontal shafts near the ends of the stove; 130

means for imparting a slow traveling motion to said belt; a plurality of rotary horizontal shafts transversely to the stove and close to each other carrying rollers on which 5 bears the upper half of the belt and another plurality of rotary horizontal shafts transversely to the stove and separated at a longer distance which are also provided with rollers on which bears the lower half of the belt; said stove having an opening provided 10 with a hopper with counterweighted door on the upper part of the roof adapted to feed onto the belt the material to be dried in the stove; and also having openings on 15 the roof for the inspection and cleansing of the stove; an outlet the front wall of the roof in level with the belt, provided with a counterweighted door which opens from in-

side to outside; a horizontal partition dividing the stove into upper and lower compartments, substantially equal, leaving end openings connecting the two compartments; a furnace whose fire-box is in communication with the lower compartment of the stove; a chimney in communication with the upper 20 compartment of the stove for discharging the combustion gases and water vapor expelled from the material when drying out; a plurality of horizontal shafts mounted above the endless belt and provided with 25 blades adapted to maintain a continued agitation of the mass of material on the belt and means for imparting a rotatory rapid motion to each one of said shafts.

In witness whereof I affix my signature.
DAVID ARANGO.
